UNITED STATES PATENT OFFICE.

MAX JANOFSKY, OF WASHINGTON, DISTRICT OF COLUMBIA, ASSIGNEE TO WINNER MANUFACTURING CO., INCORPORATED, OF WASHINGTON, DISTRICT OF COLUMBIA.

JUNCTION-BOX CONNECTOR.

1,204,120.

Specification of Letters Patent. Patented Nov. 13, 1917.

Application filed July 24, 1915. Serial No. 41,759.

To all whom it may concern:

It is known that I, MAX JANOFSKY, a citizen of the United States, and a resident of Washington, in the District of Columbia, have invented certain new and useful Improvements in Junction-Box Connectors, of which the following is a specification, reference being had to the accompanying drawings, forming a part of this specification.

18 This invention relates to improvements in connectors employed to detachably hold a flexible electric cable to a junction box; and the primary object of my invention is to provide a junction box connector of simple 16 construction insuring a secure fastening and perfect bond between the cable sheath and junction box.

Another object is to provide a junction box connector so arranged that one connector 20 or will take cables of several sizes in a manner insuring a firm connection between the box and cable.

A still further object is to provide an 26 easily operated connector that can be readily attached to hold the cable in secure position, in a manner, however, permitting the cable being instantly detached in manually manipulating a jam collar.

Finally the object of my invention is to 30 provide a simply constructed, positively operating connector that while firmly holding the cable against casual detachment, does not injure the cable sheath.

With these and other objects in view 36 the present invention consists in the combination and arrangement of parts as will be hereinafter more fully described and finally pointed out in the appended claims, it being further understood that changes in 42 the specific structure shown and described may be made within the scope of the claims without departing from the spirit of the invention.

In the accompanying drawings forming a 48 part of this specification, and in which like numerals of reference indicate similar parts in the several views:

Figure 1 shows a sectional view of a portion of a junction box with a connector embodying my invention secured thereto.

Fig. 2 is a sectional elevation of the connector, showing the same as detached.

Fig. 3 is a front view of Fig. 2.

In my present invention I provide a connector by means of which an electric cable

or sheath conductor can be readily secured to a junction box. My connector includes a jam collar working upon a tubular holding member having its forward end formed into a plurality of clamping jaws, which 60 can be forced inward to such a degree in advancing the collar that the connector will take any one of say three sizes of cables of standard make, this being possible owing to the fact that the cables are easily compressible and the jaws are yieldingly held.

In the further aim of my invention I employ a holding member including an annulus 1, having an inwardly directed stop flange 2, while from the opposite edge extend a plurality of integral equiformed spring arms 3, these arms being tubularly arranged, as shown, each arm on the inside and near its outer end having a plurality of inwardly directed gripping jaws 4, the annulus and arms being exteriorly threaded as is shown at 5, while a cam lip 6 is formed upon the outer face and near the end of each arm, as clearly shown.

Adapted to be revolvably held upon the 80 spring arms 3 is a jam collar 7 having an inner conical active surface 8 arranged for co-action with the lips 6, so that when said jam collar is advanced the spring arms are forced inward so as to securely impinge 85 upon the cable held by the holder.

As shown in Fig. 1 the holder is held 90 within an opening *a* of a junction box *A* having the flange *B* provided with the screw openings *c*, as is usual in the art.

As shown the holding member is provided with a lock nut 9, which is adapted to thread over the annulus and the spring arms. As shown these spring arms 3 are, however, only threaded a portion of their length, the 95 forward ends being smooth and unthreaded.

In securing a cable *D* the same is forced into the holder until the sheath encounters the stop flange 2. In this position a part of the insulation *E* projects through the holder, the conductors *F* in turn projecting beyond the insulation, as shown in Fig. 1.

After the holder has been inserted within the opening *a*, the lock nut 9 is tightened which results in the holder being drawn inward, during which operation the jam collar 7 is forced over the cam lip 6, resulting in the jaws being forced inward to securely clamp the cable to the junction box. After the lock nut 9 has been properly adjusted, no 110

ordinary pulling strain upon the cable will result in releasing the same from the holder.

It should be understood that these conductors are made in various sizes and of any 5 suitable material.

In the form as described the holding member is placed upon the end of the cable, which is then inserted into the opening *a* within the junction box, and not until the 10 holder is secured within the junction box are the jaws forced into engagement with the cables.

A junction box connector constructed according to my invention is simple and inexpensive and both durable and efficient in 15 operation, and can be adjusted or detached with ease, accuracy and despatch.

Having thus described my said invention what I claim as new and desire to secure by 20 Letters Patent is:

1. A connector of the class described comprising the combination with a junction box having an inlet opening, of an annulus having a plurality of equiform spring arms 25 extending from one edge each arm upon the inside and near its outer end having a plurality of inwardly directed gripping jaws said annulus and arms being exteriorly threaded, a cam lip being formed upon the 30 outer face and near the end of each arm, a jam collar having a conical active surface at one end for co-action with said lips said collar adapted to loosely work over said arms, said annulus held within said box, and 35 a nut threading upon said arms to force said collar into engagement with said box, as and for the purpose set forth.

2. The combination with a junction box having an opening, and a cable passing 40 through said opening to the interior thereof, of a member loosely held within said opening including an annulus having an in-

wardly directed stop flange limiting the inward movement of said cable and a plurality of integral equiform spring arms, 45 said arms being tubularly arranged, each arm on the inside near its outer end having a plurality of inwardly directed gripping jaws, said annulus and arms being exteriorly threaded, a cam lip being formed upon the outer face and near the end of each arm, a jam collar loosely held upon said arms and working against the outer face of said box having an inner conical active surface arranged for coaction with said lips, a lock 55 nut adapted to thread over said annulus and the spring arms working against the inner face of said junction box, whereby said annulus is drawn inward resulting in said cam lips engaging said jam collar insuring said 60 spring arms being forced upon the cable and hold the same to said junction box, as, and in the manner set forth.

3. In combination, a member comprising an annulus having an inwardly directed stop flange and a plurality of integral equiform spring arms tubularly arranged, each arm on the inside near its outer end having a plurality of inwardly directed gripping jaws, said annulus and arms being exteriorly 70 threaded, a cam lip being formed upon the outer face and near the end of each arm, a jam collar loosely held upon said arms having an inner conical active surface arranged for co-action with said lips, and a lock nut 75 adapted to thread over said annulus and said spring arms as and for the purpose set forth.

In testimony whereof I affix my signature, in the presence of two witnesses.

MAX JANOFSKY.
